Br. Marker Clark
Atty.

UNITED STATES PATENT OFFICE.

MARC GRANDJEAN, OF PARIS, FRANCE.

STENOGRAPHIC MACHINE.

Application filed January 6, 1923. Serial No. 611,093.

To all whom it may concern:

Be it known that I, MARC GRANDJEAN, a citizen of the Republic of France, and residing at Paris, Seine Department, Bourse 5 du Commerce, Rue du Louvre, in the Republic of France, have invented certain new and useful Improvements in Stenographic Machines, of which the following is a specification.

10 The present invention relates to a reel holder for stenographic machines which enables the reel to be inserted and withdrawn by one hand with great facility, and it obviates all vibrations and thus ensures 15 a perfectly silent working; the unwinding motion can also be braked, thus simplifying and even eliminating the guiding means which are required in the known devices.

For this purpose, the said reel holder comprises two arms having notches wherein are disposed the journals of the reel; two other arms are movable along the said arms and are urged by springs, these latter arms having notches disposed at an angle with the 25 first-mentioned notches and adapted to fit upon the journals and to press the same against the first-mentioned arms by means of the springs, thereby eliminating all play as well as the noise made by the journals in 30 their supports, and further providing for the braking which is necessary to prevent the reels from unwinding in an improper and troublesome manner.

To insert the reel, it is simply necessary 35 to press the journals against the movable arms in order to place the journals in the notches of the stationary arms in a ready manner; to remove the journals, the movable arms are simply let down, this being very 40 easily done, and especially when the said arms are connected together by a cross-piece.

The appended drawings shew by way of example a form of reel holder according to 45 the invention.

Fig. 1 is a plan view.

Fig. 2 is a cross-section shewing the device in the position for inserting the reel.

Fig. 3 is a like section, with the journals 50 disposed in the notches.

The said reel holder comprises an axle 1 mounted upon the journals 2 adapted to turn for example in recessed screws 3 disposed in the machine frame 4, said axle being

secured to the levers 5 having in the ends 55 thereof the longitudinal slots 6. The said arms are provided at the point where they are attached to the axle 1 with the hubs 7 wherein are formed the two notches 8 and 9 engaging the nibs 10 disposed upon the 60 spring strips 11 which are mounted upon the frame 4; the notch 8 corresponds to the operative position and the notch 9 to the position of transportation wherein the lever 5 entirely disappears within the main frame. 65

The two arms 12 connected together by the cross-piece 13 are pivoted to the levers 5 by the axles 14; the springs 15 attached to the levers 5 act upon the said cross-piece. The arms 12 have formed therein the transverse notches 16 situated opposite the notches 6; the ends of the said arms are bent at an angle in order to serve as guides for the insertion of the journals 17 of the reel. 70

To insert the reel, Fig. 2, the journals 17 75 are simply pressed against the ends of the arms 12, and when the arms come opposite the notches 16 they will rise by the action of the springs 15 and will cause the journals to bear upon the levers 5.

By this arrangement a braking action upon the journals is provided which prevents them from jumping and thus causing noise while the machine is at work, and furthermore the paper strip will be unrolled in a 85 regular manner when drawn out by the said spool, whereby the strip will be guided without the use of any special devices.

It will thus be observed that the insertion and removal of the reel can be effected with 90 one hand in a ready manner.

The invention comprises the application of the hereinbefore described reel holder or like support to all classes of stenographic machines. 95

Claims:

1. In a supporting device for the bobbin of a stenographic machine, the combination with a bobbin shaft, of two arms swingable about a common axis, each arm having a 100 longitudinally extending notch to engage said shaft, and a lever pivoted to each arm and having a transversely extending notch formed therein to engage the shaft while the latter occupies the notches of said arms. 105

2. In a supporting device for the bobbin of a stenographic machine, the combination with a bobbin shaft, of two arms swing-

able about a common axis, each arm having a longitudinally extending notch to engage said shaft, a lever pivoted to each arm and having a transversely extending notch to engage the shaft while the latter occupies the notches of the arms, a cross-piece rigidly connecting said arms together, and springs

acting upon the said arms to cause the same to exercise a braking effect upon the shaft of the bobbin.

10

In testimony, that I claim the foregoing as my invention I have signed my name.

MARC GRANDJEAN.
